COMPOUND MASTER CYLINDER

Albert E. Roy, Los Angeles, Calif.

Application March 17, 1942, Serial No. 435,003

3 Claims. (Cl. 60—54.6)

1

This invention relates to a hydraulic brake mechanism, and which is particularly adapted for use in connection with hydraulic mechanisms.

An object of my invention is to provide a novel hydraulic brake mechanism for hydraulic braking systems, whereby the initial movement of an operating lever causes sufficient pressure to be transmitted to the pressure cylinders of the braking system to actuate a brake shoe into initial contact with the braking surface of a brake drum, while further movement of the operating lever causes a high pressure to be applied to the brake cylinders for braking purposes.

Another object of my invention is to provide a novel hydraulic brake mechanism, including a low-pressure cylinder and a high-pressure cylinder, coaxially arranged, and having novel piston elements mounted on a common hub, and a single inlet for the fluid, serving both cylinders.

Another object of my invention is to provide a novel hydraulic brake mechanism, comprising a low-pressure cylinder and a high-pressure cylinder, which are in communication with one another during the initial operation of the mechanism, and including novel valve means to cut off communication between the high- and low-pressure cylinders when the piston member has moved forward on its operating stroke, and to prevent the pressure in the low-pressure cylinder from rising above a pre-determined value.

Still another object of my invention is to provide a novel hydraulic brake mechanism, including high- and low-pressure cylinders, and a novel valve-and-port means, whereby when starting the operative movement of the pistons in the cylinders, the pressure in the low-pressure cylinder, during the initial movement of the pistons, is quickly transferred to the high-pressure cylinder for the purpose of taking up slack in the brake-mechanism ports, and then pressure is transmitted at a higher value in the high-pressure cylinder by further operative movement of the pistons, and thereafter any subsequent pressure in the low-pressure cylinder is relieved during further operation of the mechanism.

A still further object of my invention is to provide a novel hydraulic brake mechanism, wherein the fluid pressure is controlled by a novel valve-and-bypass means to obtain proper balance of the fluid pressure during the compression stroke.

A feature of my invention resides in the absence of cutting on the piston cups, due to the fluid moving under high velocity, and also the rapid movement of the valve mechanism during the initial forward movement of the pistons.

2

Other objects, advantages and features of invention may appear from the accompanying drawing, the subjoined detailed description, and the appended claims.

5 In the drawing:

Figure 1 is a vertical sectional view of my hydraulic brake mechanism, and showing the piston in retracted position.

Figure 2 is a sectional view taken on line 2—2 of Figure 1.

Figure 3 is a bottom-plan view of the valve cage, and with the flat valve removed.

Figure 4 is an enlarged view of the connections between the pistons.

15 Referring more particularly to the drawing, my hydraulic brake mechanism includes a low-pressure cylinder 1 and a high-pressure cylinder 2, the high-pressure cylinder being smaller in diameter than the cylinder 1 and arranged coaxially therewith. The pressure release-and-control means is generally indicated at 3. This control-and-release means is for the low-pressure cylinder and is arranged in a fluid reservoir, and also serves to provide communication between the reservoir and the cylinder 1. A brake or operating pedal is pivoted at 5 to an arm 6, this extending from the housing of the brake mechanism. The brake pedal 4 also includes a lower arm 7, pivotally connected by a bolt 8 to one end of a push rod 9. This push rod is rounded at its inner end and engages or enters the recess 10, formed in the back of the hub 11, for the purpose of forcing the hub inwardly into the cylinders 1 and 2, upon depression of the brake pedal 4.

20 35 An oil or fluid reservoir 12 is provided with an air bleed 13, which serves to keep the reservoir in communication with the atmosphere. The hub 11 is provided with a low-pressure piston head 14 at one end, and a high-pressure piston head 15 at

40 the other end. A cup of leather, rubber, or the like 16 is provided on the low-pressure piston 14; and, similarly, a cup 17 is provided on the high-pressure piston 15. A spring 18 is positioned within the cylinder 1 and between the inner face of the piston head 14, and an abutment 19, which forms the inner end of the cylinder 2. This spring serves to return the piston assemblies to retracted or inoperative position, as shown in Figure 1. The piston assembly is retained against displacement

45 50 from the open end of the cylinder 1 by a retaining ring 20, which is seated in a suitable groove and is preferably of the snap type. The high-pressure piston 15, formed on the inner end of the hub 11, is provided with a central port 21.

55 A valve head 22 on the front end of the hub 11

seats in the port 21 to close this port on a forward movement of the hub relative to the piston 15. A plurality of ducts 23 extends through the forward end of the hub 11 and communicates with the back of the piston 15, permitting fluid to pass through the port 21, and thence into the high-pressure cylinder 2, as will be subsequently described. The piston 15 has a limited sliding movement on the hub 11, by means of a spring ring 24, slidably mounted in a slot 25 in the forward end of the hub 11. One end of the ring 24 is bent outwardly to seat in a hole or slot in the bore of piston 15 and hence the ring is movable with the piston, although its movement is confined by the slot 25 in the member 11. This limited relative movement of the piston 15 and the hub 11 enables the hub 11 to move forwardly and close the port 21, when a high pressure is applied to the brake system.

A head 26 screws into the outer end of the cylinder 2 and a delivery pipe 27 is attached thereto, this leading to the brake pistons (not shown), such as are usually provided in a braking mechanism. A boot or cover 28 encloses the open end of the cylinder 1 for the purpose of excluding dust. The relief valve assembly 3 includes a cage 29, which screws into the upper wall of the reservoir 12, and is seated in the lower wall of the reservoir. A flat valve 30 is mounted in the cage 29, and gravity normally holds this valve in open position. This valve controls a plurality of bypass ports 31, and closes these ports when the valve is forced upwardly by pressure in the cylinder 1. A small bleed port 32 is always open even when the valve 30 is closed to permit fluid to pass into the reservoir when the main check valve is closed. The main check valve consists of a ball 33, which is pressed on to its seat by a spring 34. The ball 33 is seated in the relief port 35, through which fluid is forced, as the piston 14 moves forwardly. The flat valve 30 is very light, and, therefore, will quickly close as soon as the piston 14 starts to move forwardly. A filler plug 36 is provided in the cage 29 for the purpose of replenishing the supply of fluid.

The operation of my device is as follows: Assuming the parts are initially in the released or retracted position, as shown in Figure 1, when the pedal 4 is depressed the piston assembly, including the hub 11, starts the compression stroke, and fluid in the low-pressure cylinder 1 is displaced. The valve 30 closes at once and the piston 15 is pushed forwardly, opening the port 21, and the oil flows through the ducts 23 and thence through the port 21 into the cylinder 2. This initial movement serves to immediately fill the delivery pipes, such as 27, as well as the brake cylinders, due to the large area of the piston 14 and the cylinder 1. This causes the brake shoes to engage the brake drum with a minimum movement of the pedal 4. The pressure in the cylinder 2, thereafter becomes high enough to momentarily check forward movement of the piston 15 and allow the valve head to close the port 21, after which excess fluid from the low-pressure cylinder 1 raises the ball 33, and enters the reservoir 12 through the port 35. The high-pressure cylinder 2 is now sealed against escape of fluid through any path, except through the outlet pipe 27, and continued depression of the pedal 4 applies the full pressure of fluid in the cylinder 2 to the braking mechanism. When the pedal 4 is released, the spring 18 aids in returning

the hub 11 and the attached pistons to the initial position, and also returns the pedal to retracted position. The valve 30 will now drop open and fluid from the reservoir 12 will pass through the ports 31 to refill the cylinder 1.

Having described my invention, I claim:

1. In hydraulic brake mechanism the combination with a two-stage master cylinder having high and low pressure cylinders, of a reservoir connected to said low pressure cylinder by valving mechanism which includes: a valve cage having a plurality of ports connecting said reservoir and said low pressure cylinder, one of said ports being modified to form a bleed port; a flat gravity operated valve vertically movable in said cage and adapted to close all of said ports except said bleed when pressure increases in said cylinder; and a spring operated valve connecting said cylinder and reservoir and adapted to open when said pressure increases and to close when said pressure decreases sufficiently to open said flat valve.
2. In hydraulic brake mechanism the combination with a two-stage master cylinder having high and low pressure cylinders, of a reservoir connected to said low pressure cylinder by valving mechanism which includes: a valve cage having a port connecting said reservoir and said low pressure cylinder, said port being modified to form a bleed port; a normally open valve vertically movable in said cage and adapted to close said first port but not said bleed port when pressure increases in said cylinder; and a normally closed relief valve connecting said cylinder and reservoir and adapted to open when said pressure further increases.
3. In hydraulic brake mechanism the combination with a two-stage master cylinder having high and low pressure cylinders, of a reservoir connected to said low pressure cylinder by valving mechanism which includes: a valve cage having a port connecting said reservoir and said low pressure cylinder; said port being modified to form a bleed port; a gravity operated valve vertically movable in said cage and adapted to close said first port but not said bleed when pressure increases in said cylinder; and a spring operated valve connecting said cylinder and reservoir and adapted to open when said pressure further increases.
